(57) **CLAIM**

The ornamental design for a sports bluetooth headphone, as shown and described.

DESCRIPTION

FIG. 1 is a top, front, right perspective view of a sports bluetooth headphone showing my new design;

FIG. 2 is a side view thereof;

FIG. 3 is a side view thereof;

FIG. 4 is a front side view thereof;

FIG. 5 is a back view thereof;

FIG. 6 is a bottom view thereof; and,

FIG. 7 is a top plan view thereof.

The broken lines in the drawings illustrate portions of the sports bluetooth headphone that form no part of the claimed design.
